2 Sheets-Sheet 2

UNITED STATES PATENT OFFICE.

ALICE M. KERSHAW, OF CAMBRIDGE, MASSACHUSETTS.

BROILER.

Application filed May 15, 1924. Serial No. 713,596.

To all whom it may concern:

Be it known that I, ALICE M. KERSHAW, a citizen of the United States, residing at Cambridge, in the county of Middlesex and State of Massachusetts, have invented certain new and useful Improvements in Broilers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to broilers of the gridiron type in which there is a lower grid over which is superimposed an upper grid, each having grooved or concave bars and intervening open spaces, the bars and open spaces of one grid alternating with the open spaces and bars of the other grid, and the upper grid being separable from the lower grid.

The present invention has for its object 25 to provide improved features of construction of the lower grid whereby the same will be materially strengthened and the liability of the middle portion to fracture due to contraction and expansion of the junction between the adjacent ends of the bars as heretofore disposed is materially lessened.

To the accomplishment of the foregoing and such other objects as may hereinafter appear the invention contemplates forming 35 the middle or central portion of the grid of a web with arms or members radiating from a common center, substantially at right angles to one another, with the opposite sides of each of the radiating members depressed 40 to form grooves extending parallel with the intermediate portion of each arm. Associated with the central web formed as specified are grooved ribs, each of a V-shaped formation, which alternate with 45 intervening open spaces. Other features of novel construction will be hereinafter specified.

In the drawing illustrating the preferred embodiment of the invention—

50 Figure 1 is a plan view of the complete broiler;

Figure 2 is a vertical cross-section on line 2—2 of Figure 1;

55 Figure 3 is a detail, perspective, fragmentary view of the upper and lower grids;

Figure 4 is a cross-section on line 4—4 of Figure 1;

Figure 5 is a plan view of the lower grid;

Figure 6 is a plan view of the upper grid;

Figure 7 is a detail, perspective, fragmentary view of the upper and lower grids; 60

Figure 8 is a sectional view on line 8—8 of Figure 1.

In the drawings the numeral 1 designates the base or lower grid member of the broiler 65 and 2 the upper or top member, separable one from the other. Under the present invention the lower member is composed of a centrally disposed web 3 having wings or branches 4 radiating from the center outwardly, and each wing formed at each side of its longitudinally extending central portion 5 with channels or grooves 6. The spaces between the radiating wings 4 are occupied by channeled or grooved bars 7 each 70 of a V-shaped form as shown and disposed so as to leave intervening open spaces 8 between the bars. It is preferred to make the under face of the longitudinally extending central portions of the radiating wings concave as indicated at 9 so that the flame striking the under side of the wings will be 75 directed lengthwise of the wings and thus obtain a better diffusion of the heating flame over the under side of the grid. By providing the centrally disposed web having the radiating wings the grid is braced and strengthened, and the liability to fracture due to the intensity of the flame or heat and contraction and expansion is minimized over 80 the form where the converging ends of independent grooved bars are grouped at the center of the grid as heretofore has been customary, and at the same time channels are provided at each side of the wings of the 85 web to receive the drippings from the meat on the top member of the grid.

The upper grid member 2 of the broiler is formed of a number of grooved or channeled bars or ribs 10 of a V-shaped formation as shown and disposed so as to leave intervening open spaces 11, the channeled ribs 10 lying above the open intervening spaces of the lower grid when the two grids are assembled as illustrated in Figures 1 and 100 2 of the drawing.

In order to space the upper grid from the lower grid, the upper one is formed with depending feet 12 disposed one opposite to the other and preferably in a line central 105 110

with the handle 13 of the lower grid, and for these feet are provided seats 14 formed on the lower grid as indicated in Figures 2, 5, 7 and 8 of the drawing.

5 For the purpose of preventing the upper grid from rotating on the lower grid, and also to prevent the upper grid from tilting and dropping from the lower grid when the broiler is positioned edge-up, either in 10 the suspension of the broiler, or in tilting the same for pouring from the annular gutter 15 the meat extracts or juices received therein from the channeled or grooved bars or ribs, I form the upper grid with 15 depending lugs 16, disposed opposite each other, at opposite sides of the grid, adapted to fit in openings 17 formed in the lower grid and of a width to bear against the opposite walls of the openings, and from 20 the perimeter of the grid adjacent to the lugs 16, are formed depending lugs 18 which will bear against opposite sides of bosses 19 formed on the lower grid, the lugs 18 resting on seats 20 at the opposite sides of 25 the bosses 19, as illustrated in Figures 3 and 4 of the drawing. It will be observed that the space between lugs 16 and 18 taken together forms a crotch that receives the edge of the lower grid at the inner wall 30 of the gutter at the points where the spouts 21 of the gutter 15 are located, so that when the grids are tilted for pouring the juices from the gutter the upper grid will be prevented from dropping away from the 35 lower grid. It will also be observed that by having the sides of the lugs 16 bear against the opposite side walls of the openings in which they fit, and having the lugs 18 bear against the opposite sides of the bosses 19, the upper grid is held against any rotative movement whatsoever relative to the lower grid and thus 40 the possibility of the upper grid sliding from position is positively prevented.

45 I have shown and described in detail the preferred construction of the several parts but it is to be understood that changes in some of the parts may be made without departing from the essential features sought to be defined in the appended claims.

50 Having described my invention and set forth its merits what I claim is:

1. A broiler consisting of two grids, separable one from the other, one grid including a web comprising branches radiating from a center, each branch having a channel formed therein alongside the central longitudinally extending portion of the branch, and channeled bars disposed to leave 55 intervening open spaces between the bars,

the other grid being formed with channeled bars spaced apart to leave intervening open spaces between them, the open intervening spaces of one grid registering with the channeled portions of the other grid. 65

2. A broiler consisting of two grids, one separable from the other, one grid including a web comprising branches radiating from the center, each branch having a channel formed therein alongside the central longitudinally extending portion of the branch and the central longitudinally extending portion having a concave under face, and channeled bars disposed to leave intervening open spaces between them, the other grid being formed with channeled bars spaced apart to leave intervening open spaces between them, the open intervening spaces of one grid registering with the channeled portions of the other grid. 70 75 80

3. A broiler consisting of two grids, one separable from the other, both grids having channeled bars spaced apart to leave intervening open spaces between the bars and disposed so that the intervening open spaces 85 of one grid will register with the channeled bars of the other grid, one of the grids being provided with depending lugs spaced apart to form a crotch between them and located at opposite sides of the grid, the other grid being formed with openings to receive the innermost of the crotch-forming lugs and with bosses for the outermost lugs to engage to prevent tilting and rotative movement of one grid relatively to the 90 other. 95

4. A broiler consisting of two grids, one separable from the other, both grids having channeled bars spaced apart to leave intervening open spaces between the bars 100 and disposed so that the intervening open spaces of one grid will register with the channeled bars of the other grid, one of the grids having an annular peripheral trough provided with oppositely disposed discharge 105 spouts, the other grid being formed with depending lugs disposed to enter openings in the companion grid opposite the spouts to the annular trough and formed with other depending lugs intermediate of the first 110 mentioned lugs and adapted to rest upon seats therefor formed in the other grid to space one grid from the other.

In testimony whereof I affix my signature in presence of two witnesses.

ALICE M. KERSHAW.
